UNITED STATES PATENT OFFICE.

CYRIL S. GARTON, OF SYDNEY, NEW SOUTH WALES, AUSTRALIA, ASSIGNOR OF ONE-HALF TO VALENTINE MURE FITZ HUGH, OF KERKENIN, AUSTRALIA, AND ONE-FOURTH TO PATRICK E. CUNNINGHAM AND ONE-FOURTH TO REGINALD REID, BOTH OF CHIDLWOS WELL, AUSTRALIA.

SPARK-ARRESTER.

1,032,200.

Specification of Letters Patent.

Patented July 9, 1912.

Application filed October 9, 1911. Serial No. 653,701.

To all whom it may concern:

Be it known that I, CYRIL S. GARTON, subject of the King of Great Britain, residing at Sydney, New South Wales, and Commonwealth of Australia, have invented new and useful Improvements in Spark-Arresters, of which the following is a specification.

My present invention relates to improvements in spark arresters and more especially to those applicable to locomotives for the purpose of preventing the escape of burning or glowing sparks or cinders owing to the strong draft induced by the exhaust steam which is discharged through the stack, and the primary objects of the invention are to provide an improved apparatus of this character which will not impair or diminish materially the draft of the locomotive, furnaces irrespective of whether the draft is induced by the exhaust steam during running of the engine or whether the locomotive is at rest and the draft depends upon the rising of the products of combustion, and to provide such apparatus with chambers which receive and collect the sparks, cinders and the like, such chambers being provided with means for conducting away the exhaust steam and waste gases which enter such collecting chambers with the sparks or cinders.

To these and other ends, the invention consists in certain improvements, and combinations and arrangements of parts, all as will be hereinafter more fully described, the novel features being pointed out particularly in the claims at the end of the specification.

In the accompanying drawing:—Figure 1 is an exterior elevation of a spark arrester constructed in accordance with the present invention; Fig. 2 is a top plan view, partly in section; Fig. 3 represents a vertical section on the line 3—3 of Fig. 4; and Fig. 4 represents a transverse section on the line 4—4 of Fig. 3.

Similar parts are designated by the same reference characters in the several views.

Spark arresters embodying the present invention are applicable generally to steam boiler furnaces of various kinds although the invention is particularly applicable to locomotives where the strong draft induced by exhaust steam from the locomotive cylinder causes ordinarily the discharge of burning or glowing sparks or cinders from the stack, and such burning cinders if permitted to escape are liable to cause fires and other damage. The spark arrester in the present instance is particularly applicable to locomotives, it comprising an inner tubular casing 1 which leads from the smoke-box of the locomotive and receives the products of combustion therefrom, the draft through the boiler, smoke-box and the inner chamber 1 being induced as usual by the exhaust nozzle 2 the outlet of which is directed axially of the chamber 1. The inner chamber 1 is enclosed or surrounded by an outer casing 3, the upper portion of which is preferably enlarged as shown and is covered by a top plate 4 which may be removably held in position by the bolts 5 to permit access to the interior of this chamber, and the top plate has an opening 6 in alignment with the inner chamber 1 through which the products of combustion are discharged, this opening in the present instance being shown as provided with a surrounding flange 7 to which a stack may be applied if desirable or necessary. The lower portion of the outer chamber 3 is preferably narrower than the upper portion and it forms a pair of chambers 8 at opposite sides of the inner casing 1, these chambers 8 serving to receive and collect the sparks, cinders and other waste products of combustion from the locomotive furnace. The bottoms of the chambers 8 may be provided with suitable outlets whereby the accumulated cinders may be discharged.

The upper enlarged portion of the outer casing 3 contains a pair of oppositely mounted bladed spark-controlling and arresting members 9, each of these members embodying a shaft 10 which is journaled at its opposite ends in the opposite sides of the outer casing 3 and each shaft carries a suitable number of radially projecting blades 11 the outer edges of which are turned laterally to form spark-retaining flanges 12. The blades 11 are preferably composed of wire mesh or screen material of suitable mesh to prevent the passage of sparks therethrough but of a mesh sufficiently large to permit the consumed gases to pass through these blades. The shafts 10 of the two spark-controlling members are in parallelism and at opposite

sides of the inner casing 1 and these shafts are operatively connected in a manner that will insure an interengaging of the blades of the two members, that is to say, each 5 blade of one of the members engages between two adjacent blades of the opposed member, the two members being freely revolute but in unison so that this relation between the members is maintained. Any suitable 10 means may be provided for operatively connecting the spark members so as to maintain this relation, a connecting shaft 13 being provided in the present instance having bevel gears 14 which coöperate with bevel gears 15 on the respective ends of the shafts 10. The spark-controlling members are oppositely mounted or in opposed relation and so placed that their interengaging blades extend completely across the outlet at the top 15 of the inner casing 1 so that the gases passing upwardly through and discharging from the inner casing 1 must either pass through these interengaging blades or, if the draft of such gases is sufficiently strong, an impulse 20 will be imparted to the bladed members, causing these members to revolve simultaneously in reverse directions, the perforated blades then moving with the ascending gases and avoiding any material obstruction there- 25 to. When the locomotive is at rest, that is to say, no exhaust steam is discharging from the exhaust nozzle, the escaping gases may flow freely through the perforated or mesh blades of the two members and will escape 30 to the stack without encountering any substantial resistance. When, however, the draft is induced by exhaust steam projected from the exhaust nozzle, the impact of such gases upon the interengaging blades of the 35 spark-controlling members will cause these members to revolve simultaneously in reverse directions and the blades will then move with the ascending or discharging gases although there will be no direct outlet 40 for the discharging gases as such gases must impinge against or pass through the mesh blades. The spark-catching flanges 12 on the outer edges of the blades of the spark-controlling members, which flanges extend 45 rearwardly with respect to the direction of movement of the blades, serve to retain the sparks on these members and to prevent the sparks from being thrown upwardly or through the stack owing to the centrifugal 50 force of the revolving members. When the sparks reach positions at opposite sides of the axes of the members, they are discharged into the spark-collecting chambers 8 and these chambers 8 will also receive such exhaust 55 steam and waste gases as accompany the sparks. In order to effectively remove the sparks from the respective revolute members and to prevent these sparks from being thrown toward the outlet of the inner 60 casing 1, it is preferable to provide a suit- 65

able number of stationary vertically disposed vanes 16 immediately adjacent to the periphery of the respective spark-controlling member and at the inlet or entrance to the corresponding spark-collecting chamber 70 8, these vanes serving to draw the sparks from the revolute members and to insure their discharge into the respective collecting chambers.

The present invention provides simple and effective means for discharging the exhaust steam and waste products of combustion which enter the chambers 8 with the sparks. In the present instance, a pair of diaphragms or partitions 17 are applied to the opposite sides of the inner casing 1 and they extend completely across and join with the side walls of the outer casing 3, thus forming a set of four passages 18 spaced equidistantly in or about the circumference of 80 the inner casing 1. Each partition 17 is formed with an outlet 19 leading into the respective passage 18 and an angularly disposed deflector 20 is connected to the partition 17 at a point immediately above the 85 respective outlet 19 whereby the exhaust steam and waste gases which have a tendency to rise in the spark-collecting chambers 8 will be guided by the deflector 20 into the respective outlets 19, such steam and 90 gases thus entering the respective passages 18, and each of these passages 18 has a discharge 21, there being two of these discharges at each side of the outer casing in the present instance. The exhaust steam 95 and waste gases in passing out through the discharges 21 are conducted away in the present instance by a pipe 22 which has a pair of branches 23 which embrace the opposite sides of the outer casing, and each 100 branch has a pair of inlets which communicate with the discharges 21. By conducting away the exhaust steam and waste gases in this manner, the draft through the inner casing 1 is not obstructed and, moreover, the 105 revolute spark-controlling members are substantially free of back pressure and, hence, these members will effectively receive the sparks and they will revolve easily so that the blades will move at substantially 110 the rate of movement of the gases exhausted from the inner chamber 1, back pressure upon the exhausting gases being thereby minimized.

I claim as my invention:—

1. A spark arrester comprising, in combination, an inner discharge casing for the products of combustion, an outer casing forming spark-collecting chambers below the discharge outlet of the inner casing, a 125 pair of oppositely mounted revolute spark-arresting members above the inner casing and having interengaging blades disposed above the outlet of the inner casing, said members being operative to discharge the sparks into 130

said collecting chambers, and means for conducting exhaust steam and waste gases from the spark-collecting chambers.

2. A spark arrester comprising, in combination, an inner discharge casing for the products of combustion, an outer casing forming spark-collecting chambers below the discharge outlet of the inner casing, a pair of oppositely mounted revoluble spark-arresting steam and gas-discharging passages, and having interengaging blades disposed above the outlet of the inner casing, said members being operative to discharge the sparks into said collecting chambers, partitions mounted in the outer casing and forming separate steam and gas-discharging passages, said partitions having steam and gas outlets and deflectors for conducting the steam and gas into such outlets, and means for collecting and conducting the steam and gas from said passages.

3. A spark arrester comprising, in combination, an inner discharge casing for the products of combustion, an outer casing forming spark-collecting chambers below the discharge outlet of the inner casing, a pair of oppositely mounted revoluble spark-arresting members above the inner casing and having interengaging blades disposed above the outlet of the inner casing, said members being operative to discharge the

sparks into said collecting chambers, partitions mounted in the outer casing and forming separate steam and gas-discharging passages, said partitions having steam and gas outlets and deflectors for conducting the steam and gas into such outlets, and means for collecting and conducting the steam and gas from said passages.

4. A spark arrester comprising, in combination, an inner casing for the discharge of products of combustion, an outer casing forming spark-collecting chambers, oppositely mounted revoluble members above the outlet of the inner casing having blades for catching and conveying the sparks to said collecting chambers, and vanes mounted at the periphery of each revoluble member and at the entrance to the respective collecting chamber for removing the sparks from the revoluble members and directing them into said chambers.

In testimony whereof I have hereunto set my hand in presence of two subscribing witnesses.

CYRIL S. GARTON.

Correction in Letters Patent No. 1,032,200.

It is hereby certified that in Letters Patent No. 1,032,200, granted July 9, 1912, upon the application of Cyril S. Garton, of Sydney, New South Wales, Australia, for an improvement in "Spark-Arresters," an error appears in the printed specification requiring correction as follows: Page 3, line 10, strike out the words "steam and gas-discharging passages, and" and insert the syllables and words *resting members above the inner casing and*; and that the said Letters Patent should be read with this correction therein that the same may conform to the record of the case in the Patent Office.

Signed and sealed this 8th day of October, A. D., 1912.

[SEAL.]

C. C. BILLINGS,

Acting Commissioner of Patents.
